UNITED STATES PATENT OFFICE.

ARTHUR B. PROAL, JR., OF NEW YORK, N. Y.

APPARATUS FOR EXCAVATING AND REMOVING MATERIAL.

No. 874,865.

Specification of Letters Patent.

Patented Dec. 24, 1907.

Application filed April 1, 1907. Serial No. 365,865.

To all whom it may concern:

Be it known that I, ARTHUR B. PROAL, Jr., a citizen of the United States, residing in the city, county, and State of New York, have invented a new and useful Improvement in Apparatus for Excavating and Removing Material, of which the following is a specification.

This invention relates to apparatus for excavating and removing material, and, in its preferred form, comprises excavating apparatus, such as a steam shovel, a conveyer adapted to receive material from the excavating apparatus, means for discharging material from the conveyer and cars arranged to receive the material as it is discharged from the conveyer.

As is well known, the capacity of a steam shovel or other analogous excavating apparatus to excavate a trench or the like is limited, but is determined in part by the time required to remove the cars filled with excavated material and supply empty cars in place of the filled cars removed. Ordinarily, a steam shovel or other similar excavating apparatus discharges the excavated material directly into a single car standing alongside of the excavating apparatus, and, after having been filled, the car must be removed and an empty car brought into position alongside of the excavating apparatus. When the excavating apparatus stands alongside of a track extending away from the excavating apparatus in two directions, the removal of a full car and the substitution of an empty one in position to receive the excavated material can be accomplished without interrupting the operation of the excavating apparatus. When, however, a steam shovel is at use in digging a trench and is working at the end of the trench, it is impossible to effect the removal of a car filled with material and the substitution of an empty car in position to receive material from the excavating apparatus without interrupting the operation of the excavating apparatus for a considerable period of time.

The present invention is designed to obviate the interruption of the operation of excavating apparatus under the circumstances recited and thereby to increase the quantity of material which can be excavated and removed by means of a single excavating apparatus of given capacity and cars to receive the excavated material.

In the accompanying drawings, in which

corresponding parts are designated by similar characters of reference, I have illustrated a typical embodiment of my invention, but it is to be understood that I do not limit myself to the precise form of any of the elements illustrated and hereinafter described, as variations in the elements may be made without altering the scope of the invention or sacrificing the advantages thereof.

In the drawings: Figure 1 and Fig. 1^a are a plan view of a portion of the trench in process of excavation and of apparatus embodying the present invention in use in the excavation of the trench. Fig. 2 and Fig. 2^a are a view in side elevation of the apparatus shown in Fig. 1, shown in relation to the trench which is in process of excavation. Fig. 3 is a transverse sectional view through the trench and the apparatus on the plane 3—3 of Fig. 2. Fig. 4 is a detail view of a form of closure for the lower end of the delivery chute of the tripper.

Referring to the drawings, 1 designates a track upon which the steam shovel or other excavating apparatus 2 is advanced into the trench 3 as the excavation is carried forward, and 4 designates a track parallel to the track 1 on which is supported a conveyer designated generally as 5 and comprising a plurality of wheeled supports 6 upon which an endless conveyer belt 7 or its equivalent is mounted. Most of the wheeled supports 6 are of such height that a tripper 8, arranged to travel thereover will deliver material from the belt 7 into cars 9, standing on the track 1 behind the excavating apparatus 2. The conveyer support adjacent to the excavating apparatus, however, presents an inclined bed over which the conveyer ascends to the height of the other supports, and at the lower end of this support there is mounted a receiving hopper 10 for the material excavated. The hopper 10 is preferably of such capacity that it can receive all the material excavated by the excavating apparatus in a suitable number of operations without overflow. From this receiving hopper 10 the excavated material passes under the influence of gravity to the conveyer belt 7 over which it passes to the tripper or deliverer 8, by which it is discharged from the belt and delivered through an inclined chute 11 to the cars 9 arranged parallel to the conveyer.

In the operation of the apparatus above described, the excavating apparatus and the conveyer belt operate continuously until the

entire number of cars 9 have been filled. During the filling of these cars the tripper 8 may make a number of trips to and fro at tolerably high speed or it may be propelled 5 slowly so that a single movement of the tripper in one direction only is sufficient to effect the filling of all the cars in the train. To avoid dropping the excavated material between the ends of the cars 9 as the tripper 10 passes from car to car, it is desirable to provide a discharge chute 11 with some sort of closure whereby the flow of material through the chute may be interrupted while the tripper passes from one car to the next. To this 15 end, I provide a hinged section 12 at the lower end of the chute 11 and a gravity catch 13 by which the hinged section of the chute may be held in the position indicated in dotted lines in Fig. 4. After the tripper has 20 passed from one car to the next, the operator can easily release the pivoted section of the chute by raising the catch 13 and the delivery of material can be instantly renewed.

After the filling of the cars 9 of the train, 25 an engine can be attached to the rear extremity of the train and the cars can be quickly removed from the section of track adjacent to the excavating apparatus, thus leaving this portion of the track open for 30 another train. To facilitate the removal of the train of loaded cars and its replacement by a train of empty cars, the two tracks 1 and 4 are connected by switch tracks 14 and 15. If two engines are available, one of them attached to the train of empty cars 9^a may be 35 standing on the track 1 in position to be moved up behind the excavating apparatus as soon as the filled cars 9 are hauled out over the switch track 14 and on to the track 4. If 40 only one engine is available, the cars 9^a may be brought into the position shown and the engine may then be detached, brought on to the track 4 over the switch track 15 and then again on to the track 1 between the filled cars 45 and empty cars by travel over the switch track 14. The filled cars can then be drawn on to the track 4 over the switch track 14 and the engine can be returned to the track 1 over the switch track 15 and attached to the 50 train of empty cars preparatory to moving it into position to receive excavated material from the conveyer. Whether one or two engines be used, the time required to replace the filled cars with empty cars is very short 55 and, if the receiving hopper 10 be of proper capacity, the operation of the excavating apparatus need not be interrupted while the change of cars is made. Of course, however, when a change of cars is in progress, the discharge of material from the conveyer must be 60 stopped, and it is desirable that the operation of the conveyer be stopped while the loaded cars are being replaced by empty ones. This is preferable to the provision of a storage hopper upon the tripper and the contin-

ued operation of the conveyer when the tripper is not actually delivering material to the cars.

While I have shown a train of five cars for receiving the excavating material and have illustrated a conveyer of corresponding length, it is obvious that the length of the train of cars and of the conveyer may be increased or diminished as desired. It will also be noted that the supports of the conveyer, being carried on wheels which preferably rest upon track rails, the conveyer and the excavating apparatus can be advanced without difficulty as the work of excavation is carried forward, and, when it is desired to shift the position of the excavating apparatus laterally, the conveyer can be shifted at the same time and in similar manner by simply relaying the track upon which it stands. By shifting the conveyer to track 1 and placing the excavating apparatus on track 2, the range of operation of the excavating apparatus can be altered as indicated by the broken line in Fig. 1.

Having thus described my invention, what I claim as new and desire to secure by Letters Patent is:

1. The combination with excavating apparatus, of a conveyer adapted to receive material from the excavating apparatus, and means for delivering material from said conveyer to cars adjacent to said conveyer.

2. The combination with excavating apparatus, of a receiving hopper into which said excavating apparatus is adapted to deliver, a conveyer on to which said receiving hopper discharges, and means for discharging material from conveyer to cars adjacent to said conveyer.

3. The combination with excavating apparatus, of a conveyer to which said excavating apparatus is adapted to deliver, said conveyer having a portion thereof elevated, and means for delivering material from the elevated portion of said conveyer to cars adjacent to said conveyer.

4. The combination with excavating apparatus, of a conveyer adapted to receive material from said excavating apparatus, and a traveling tripper or deliverer for said conveyer whereby material may be delivered from said conveyer to cars standing alongside of said conveyer.

5. The combination with excavating apparatus, of a conveyer adapted to receive material from said excavating apparatus and a tripper or deliverer for discharging material from said conveyer into the cars arranged alongside of said conveyer, said tripper having a discharge chute provided with a closure, whereby the delivery of material through said discharge chute may be arrested when said tripper or deliverer is in transit from one car to another.

6. The combination with portable excavating apparatus, of a portable conveyer

adapted to receive material from said excavating apparatus, and means for delivering material from said conveyer to cars adjacent to said conveyer.

5 7. The combination with a steam shovel, of a conveyer adjacent to said steam shovel and adapted to receive material excavated thereby, and means for discharging material

from said conveyer into cars adjacent to said conveyer.

In testimony whereof, I have signed my name in the presence of two witnesses.
